TRANSPOSED COAXIAL CONDUCTOR SYSTEM

William H. Doherty, Summit, N. J., assignor to Bell Telephone Laboratories, Incorporated, New York, N. Y., a corporation of New York

Application July 7, 1953, Serial No. 366,510

3 Claims. (Cl. 333—96)

This invention relates to improvements in electromagnetic transmission structures or tuned cavities.

The object of the present invention is to reduce the losses in transmission lines or resonant cavities.

It has previously been proposed to use Litzendraht conductors, consisting of a large number of strands of fine wire that are insulated from each other except at the ends where the various wires are connected together, to reduce losses at lower frequencies. At frequencies above about one megacycle, however, capacitive effects and stranding irregularities make Litzendraht conductors impractical.

In accordance with the present invention, losses in conductive surfaces at high frequencies are reduced by the use of two or more superposed conductive layers which are insulated from one another and which are periodically transposed, forcing current to flow in all the layers, instead of just in the "skin" of a single surface. In one specific embodiment of the invention, the center conductor of a coaxial line is made up of a series of thin concentric cylindrical conducting shells which are periodically transposed. In contrast to Litz wire, the present structures are eminently suitable for high frequencies, the laminated conducting elements do not require any direct electrical connection, and the currents are induced in the conducting laminations by an electromagnetic wave passing down a wave guiding passageway.

Other objects and various features and advantages of the invention will be developed in the course of the detailed description of the drawings. In the drawings:

Fig. 1 is a schematic illustration of a coaxial line having a transposed multi-layer center conductor;

Fig. 2 is a cross sectional view of a transposed conductor structure which could be used for the center conductor of the coaxial line of Fig. 1; and

Fig. 3 shows an alternative transposed conductor structure.

Referring more particularly to the drawings, Fig. 1 shows by way of example and for purposes of illustration a coaxial line energized by a high frequency signal generator 11. The coaxial line includes an outer conductor 12, and an inner conductor having two concentric layers 13 and 14. These layers are periodically transposed as indicated at transposition points 15, 16, 17, and 18, and can be spaced apart from one another by the insulation layer 19. Similarly, the wave guiding passageway between the outer conducting layer 13 of the central conductor structure and the outer coaxial conductor 12 can be completely filled with the solid dielectric layer 21. Spaced dielectric beads may, however, be substituted for the layer 21 in a manner which is well known in the art. The thin conducting shells which make up the active elements of the composite center conductor are provided with an insulating core comprising the insulation layer 22 and a central wire 23. This central wire 23 is insulated from the conducting shells 13 and 14 throughout its length, and can be constructed of copper or steel

2

to conduct power to repeater points or to add strength to the cable structure, respectively.

Although the individual conducting shells or layers may be as thick as is considered desirable from a construction viewpoint, optimum electrical properties are obtained with thicknesses of not more than one or two skin depths. Another construction matter which should be noted is the alternative of constructing each conducting layer from untransposed laminations of conducting and insulating material. This alternative structural configuration improves the current distribution in the individual layers and avoids proximity effects due to currents in other layers, which may otherwise tend to limit the improvement in transmission obtained by applicant's structure.

The purpose of this transposed multi-layer conducting structure is to increase the effective penetration or skin depth of the current, and thus reduce transmission losses. As applied to the device of Fig. 1, the signal generator 11 excites an electromagnetic field in the wave guiding passageway between conductors 12 and the composite center conductor structure, and current flows in the outer surface of the conducting shell 13₁ of the first transposition section of the center conductor. As conductor 14₁ is shielded from the field by conductor 13₁, little or no current flows in this section. At transposition point 15, however, the outer conducting shell 13₁ is connected to the inner conducting shell 14₂ of the second transposition section. Current is thus carried by both the inner and outer conducting shells of the composite center conductor in the second and all successive transposition sections of the transmission line, giving substantially higher conductivity and lower losses than if the center conductor were solid and the current carried by the outer surface or "skin" of the single conductor. It is obvious that, as alternatives to the foregoing, the current can be introduced into the structure on the inner conductor, or on both or all conductors simultaneously.

In order to assure a uniform current distribution between the two inner concentric conductive surfaces 13 and 14 and to minimize distortion of the field between the outer conductor 12 and the composite inner conductor, the transposition sections should be relatively small as compared to one-quarter of the propagation wavelength λ_p of the signal which is transmitted down the coaxial line. Thus, although any transposition interval less than one-quarter wavelength gives substantially improved results as compared with the usual type of coaxial line, transposition lengths of one-sixteenth wavelength or less are preferred. In addition, it might be noted that under appropriate conditions transposition intervals of several hundred feet or more might still fulfill the above-noted limitations. This would correspond to greatly increasing the length of the straight sections between the transition points in the structures shown in the drawings.

Figs. 2 and 3 illustrate specific structures involving interleaved tabs which may be used for the center conductor structure of the coaxial line of Fig. 1.

In Fig. 2, a detailed view of one form of construction is shown, with all elements except the inner conducting layers 13 and 14 and the intermediate insulation layer 19 deleted for purposes of clarity. At the transposition point 15 between the first and second transposition sections, the conducting tab 27 interconnects the outer conducting shell 13₁ of the first transposition section with the inner conducting shell 14₂ of the second section, and the tab 28 interconnects inner and outer conducting elements 14₁ and 13₂, respectively. In order to allow adequate clearance for the tabs and still provide maximum conductivity, each tab has an angular extent of approxi-

mately 120 degrees. With the two tabs located at diametrically opposed points of the conducting cylinders, this arrangement allows 60 degrees clearance as the tabs pass each other. One of the two diametrically opposed tab clearance spaces is shown at 29 in Fig. 2 between tabs 27 and 28. The structure described for transition point 15 is duplicated at points 16, 17, 18 and at successive transition points.

In Fig. 3 a composite center conductor structure having three layers 31, 32, 33 is shown, with the increased number of conductors serving to further reduce the resistive losses in this center conductor structure. With a view toward maintaining good conductivity between conducting shells, only two transitions are effected at each transition point. In order to carry out this design, the outer conducting cylinders or shells 31₁, 31₂, 31₃ are offset with respect to the inner conducting shells 33₁, 33₂, 33₃, and the intermediate conducting shells 32₁ through 32₅ are of approximately one-half the length of the inner and outer conducting cylinders. In addition, these intermediate cylinders 32₁ through 32₅ are located longitudinally so that the spaces between adjacent cylinders successively coincide with the spaces between the inner cylinders 33₁ through 33₃ and the spaces between the outer conducting cylinders 31₁ through 31₃. At these common spaces between cylinders or transition points tabs similar to those shown in Fig. 2 cross-connect successive cylinders of different radii so that the current induced in the outer conducting sections 31 is progressively directed downwardly through the intermediate conducting sections 32 to the inner conducting shells 33, and then is directed back to the outer surface of the central conductor structure again. Referring to the outer conducting shell 31₁ at the lefthand end of the conductor structure shown in Fig. 3, current is led away from this outer shell 31₁ and inwardly to the conducting cylinder 32₂ by means of the conducting tab 37 which overlies and interconnects these two cylinders. Incidentally, this tab 37 has a substantial peripheral extent and has very nearly the same diametrically opposed relationship with tab 38 as tabs 27 and 28 of Fig. 2 have for one another. After traversing the length of conducting cylinder 32₂, the current is led inwardly through tab 41 to the inner conducting shell 32₂ and then is led back outwardly to section 32₅ via tab 42. By examining the other interconnections shown in this structure, it can readily be seen that there are three parallel conductive paths which help carry the current along the length of the structure and thus reduce the transmission losses, and that these paths are insulated from one another by layers of the insulating material 34.

Although the foregoing description has dealt principally with the inner conducting structure of a coaxial line, the invention is by no means limited to this arrangement. For example, the outer conductor of a coaxial line could have several transposed layers included in its structure. It is generally desirable for shielding purposes, however, to have the outermost conducting layer continuous. Furthermore, the principles of the invention are also applicable to resonant chambers and wave guides. In the case of wave guides, one or more of

the walls are of multi-layer construction and are periodically transposed in much the same manner as suggested above for the center conductor structure of the coaxial line.

As mentioned hereinbefore the individual conducting layers need not be connected together at the ends of the cable for high frequency transmission. However, for the transmission of lower frequencies, various of the conducting layers may be connected in parallel to provide one or more pairs of conducting paths.

It is to be understood that the above-described arrangements are illustrative of the application of the principles of the invention. Numerous other arrangements may be devised by those skilled in the art without departing from the spirit and scope of the invention.

What is claimed is:

1. In an electromagnetic wave transmission system for use over a predetermined range of wavelengths, an extended coaxial transmission line comprising a continuous outer conducting member, a composite internal coaxial conductor comprising a plurality of conducting and insulating laminations including an inner conducting layer, an outer conducting layer, and one or more intermediate conducting layers, and means for transposing said conducting laminations at intervals along the transmission line length, the means for transposing the said inner layer with one of said intermediate layers being spaced axially from the means for transposing one of said intermediate layers with the said outer layer.

2. In an electromagnetic wave transmission system for use over a predetermined range of wavelengths, an extended coaxial transmission line as claimed in claim 1 wherein the means for transposing said conducting laminations comprises a plurality of substantially flat conducting tabs having a greater width than thickness.

3. In an electromagnetic wave transmission system for use over a predetermined range of wavelengths, an extended coaxial transmission line comprising a continuous outer conducting member, a composite internal coaxial conductor comprising a plurality of conducting and insulating laminations including an inner conducting layer, an outer conducting layer, and one or more intermediate conducting layers, means for transposing said conducting laminations at intervals along the transmission line length, the means for transposing the said inner layer with one of said intermediate layers being spaced axially from the means for transposing one of said intermediate layers with the said outer layer, and means including a signal source for launching wave energy onto said conducting laminations in parallel.
